SAFETY DEVICE FOR CUTTER ROLLERS OF CIGAR MACHINE

Filed Oct. 25, 1932

UNITED STATES PATENT OFFICE

1,984,813

SAFETY DEVICE FOR CUTTER ROLLERS
OF CIGAR MACHINESWalter H. Schussler, Philadelphia, Pa., assignor to
International Cigar Machinery Company, a cor-
poration of New Jersey

Application October 25, 1932, Serial No. 639,465

4 Claims. (Cl. 131—49)

This invention relates to an improved safety device for cutter rollers of cigar machines. The main object of the invention is to stop the machine in case of an obstruction on the cutting bed, thereby preventing injury to the hands of a careless or slow operator. With this and other objects not specifically mentioned in view, the invention consists in certain constructions and combinations hereinafter fully described and then specifically set forth in the claims hereunto appended.

Heretofore safety devices on cigar machines were arranged so that only the cutter rollers would be stopped when an obstruction was on the wrapper die, while the rest of the machine continued its movements. The advantage of the present device is that in case of an obstruction on the wrapper die the whole machine comes to a stop and no bunches in preparation will be lost.

In the accompanying drawing which forms a part of this specification and in which like characters of reference indicated the same or like parts:

Fig. 1 is a plan view, showing the improved cutter roller and safety device arrangement; and

Fig. 2 is an enlarged view of a portion of Fig. 1, showing the actuating parts of the device.

In carrying the invention into effect there is provided a drive shaft, a clutch device for driving the shaft, a cutting bed, means driven from the shaft and cooperating with the cutting bed to cut a wrapper from a wrapper leaf on the bed, mechanism actuated by an obstruction on the cutting bed to disengage the clutch, and automatic means for locking the clutch device in disengaged position. In the best forms of construction contemplated the clutch device includes a driven pulley loosely mounted on the drive shaft, a clutch member splined on the drive shaft and engaging the pulley, and a yoke engaging said clutch member and adapted to shift it out of engagement with the pulley, and the locking means includes a spring-tensioned lever adapted to retain the yoke in shifted position. In the preferred form of construction the cutting means includes a pivoted cutting arm arranged to swing over the cutting bed and actuated from the drive shaft to swing about its pivot over the cutting bed, and said mechanism includes a safety arm pivoted on the cutting arm, a stop bracket loosely mounted on the pivot of the cutting arm and connected to the clutch device, and a wedge on the safety arm adapted to clamp the safety arm to the stop bracket, when the motion of the safety arm is obstructed, thereby disengaging the clutch.

These various means and parts may be widely varied in construction within the scope of the claims for the particular device selected to illustrate the invention is but one of many possible concrete embodiments of the same. The invention, therefore, is not to be restricted to the specific construction shown and described.

In a cigar machine, the wrapper leaf is spread by an operator on a cutting bed where the leaf is held by suction. The cutting bed used in the present embodiment of the invention is of usual construction and consists of a suction shell 5, a wrapper cutting die 6 and a wrapper head 7. A cutting arm 8, also of usual construction, and carrying a pair of cutting rollers 9 then passes over the die 6 and cuts a leaf section from the leaf, whereupon the cutting arm returns the cutting rollers 9 to inoperative position. The leaf section is removed from the wrapper head 7 by means of a wrapper carrier (not shown), and applied either as a binder in the formation of a cigar bunch, or as a wrapper in the formation of a cigar from a cigar bunch. The cutter arm 8 is pivoted on a stud 10 and is equipped with a lever 11 connected through a link 12 to a bell crank lever 13 pivoted to stud 14 which is held by a bearing bracket 15. Bell crank lever 13 by means of link 16 is actuated from a cam lever 17 carrying a cam roller 18 engaging in a cam track 19 of cam 20 mounted on shaft 21. Cam lever 17 is pivoted to a stud 22 supported by bracket 15. Shaft 21 is driven by means of a bevel gear 23 meshing with a bevel gear 24 mounted on shaft 25 which carries a slidable friction clutch 26 splined thereon and engaging with a pulley 27 loosely mounted on shaft 25 and driven by means of belt 28 from the main drive of the machine. Cutting arm 8 which is oscillated by means of cam 20 carries a safety arm 29 pivoted to stud 30. To safety arm 29 is fastened an eccentric wedge 31 which by movement of the arm 29 in the direction of the arrow, Fig. 2, will engage with the clamping surface 32 of stop bracket 33, thereby causing motion of the latter which is pivoted on stud 10 in the same forward direction as arm 8. Stop bracket 33 is equipped with a lever 34 engaging with a yoke 35 operating the friction clutch 26. The yoke 35 is pivoted to a stud 36 fastened to the main frame of the machine. A tension spring 37 causes arm 29 to rest against stop stud 38, assuring a clearance between wedge 31 and clamping surface 32 during normal operation. It is only when an obstruction strikes arm 29 that wedge 31 engages with clamping surface 32 of bracket 33 causing

the disengagement of friction clutch 26 and thereby stopping the machine. In order to prevent spring 39 from engaging clutch 26 before the trouble in the machine is corrected, a lock 5 lever 40 is provided which by means of a light tension spring 41 pulling the lock lever against the stop pin 45, follows the movement of yoke 35 when disengaging clutch 26, thereby keeping yoke 35 from retreating and assuring that the 10 clutch remains in disengagement until the trouble in the machine is corrected. Lock lever 40 is provided with a hand lever 42 and pivoted on a stud 43 mounted in the main frame of the machine. The re-starting of the machine is effected by operating hand lever 42 in such a 15 manner as to release lock lever 40 from lever 35, whereupon spring 39 seated against collar 44 mounted on shaft 25 actuates and engages clutch 26 again.

20 20. What is claimed is:

1. The combination with the drive shaft of a cigar machine, of a clutch device for driving said shaft, a cutting bed, means driven from said shaft and cooperating with said cutting bed to cut a 25 leaf-section from a wrapper leaf on said bed, mechanism actuated by an obstruction on the cutting bed to disengage said clutch device, and automatic means for locking the clutch device in disengaged position.
2. The combination with the drive shaft of a 30 cigar machine, of a clutch device for driving said shaft, a cutting bed, means driven from said shaft and cooperating with said cutting bed to cut a leaf section from a wrapper leaf on said bed, mechanism actuated by an obstruction on the 35 cutting bed to disengage said clutch device, and automatic means for locking the clutch device in disengaged position, said clutch device including a driven pulley loosely mounted on the drive 40 shaft, a spring-pressed clutch member splined

on the drive shaft and engaging said pulley, and a yoke engaging said clutch member and adapted to shift it out of engagement with said pulley, and said locking means including a spring-tensioned lock lever adapted to retain the yoke in shifted 5 position.

3. The combination with the drive shaft of a 10 cigar machine, of a clutch device for driving said shaft, a cutting bed, means driven from said shaft and cooperating with said cutting bed to cut a 15 leaf-section from a wrapper leaf on said bed, mechanism actuated by an obstruction on the cutting bed to disengage said clutch device, and automatic means for locking the clutch device in disengaged position, said cutting means including a cam geared to said drive shaft, a cam lever operated by said cam, a cutting arm connected to said cam lever, and cutting rollers on said arm arranged to engage the tobacco leaf on the cutting bed.

4. The combination with the drive shaft of a 20 cigar machine, of a clutch device for driving said shaft, a cutting bed, means driven from said shaft and cooperating with said cutting bed to cut a 25 leaf-section from a wrapper leaf on said bed, mechanism actuated by an obstruction on the cutting bed to disengage said clutch device, and automatic means for locking the clutch device in disengaged position, said cutting means including a pivoted cutting arm arranged to swing over 30 the cutting bed, and means driven from the drive shaft for swinging said cutting arm about its pivot over the cutting bed, and said mechanism including a safety arm pivoted on said cutting arm, a stop bracket loosely mounted on the pivot of 35 said cutting arm and connected to the clutch device, and a wedge on said safety arm adapted to clamp the safety arm to the stop bracket when the motion of the safety arm is obstructed.
